KITCHEN MACHINE

Erik Oskar Helge Hansson, Stockholm, Sweden,
assignor to Aktiebolaget Electrolux, Stockholm, Sweden, a corporation of Sweden

Application February 7, 1948, Serial No. 6,972
In Germany December 7, 1942

Section 1, Public Law 690, August 8, 1946
Patent expires December 7, 1962

9 Claims. (Cl. 248—19)

1

This invention relates to a machine for effecting operations in a kitchen, such as kneading, mixing, grinding and the like, an example of such type of machine being found in U. S. Patent No. 2,270,164, dated January 13, 1942.

The present invention has reference to means by which a machine of this character may be supported in two positions to permit of its operation while in either position. According to the present invention, the machine includes a standard in which a pivotal arm is mounted, said pivotal arm carrying a work tool, such as a roller, and means is provided by which the pivotal arm can be locked in different positions of angular adjustment, said means including a locking member which will act as a supporting foot for the machine when the machine is disposed in one of its operative positions.

Another object of the invention is to provide, in a machine of this character, supporting elements or feet, arranged in groups and intended for the support of the machine in either of two positions, one of the feet in one of the groups being composed of a locking element for a movable arm of the machine, means being provided for normally swinging the arm to a position whereby said locking element is so disposed so that it can perform its supporting function. The invention further contemplates the arrangement of a locking means for said swinging arm by means of which the arm may be moved to any selected position within its range of swinging movement and maintained in such position.

In the accompanying drawing, wherein an illustrative embodiment of the invention is disclosed:

Fig. 1 is a side elevation of a kitchen machine arranged in a position wherein the adjusting and locking member for the swinging arm is serving as a supporting foot or rest for the machine;

Fig. 2 is an end view, partly in section in the line 2—2 of Fig. 1, looking in the direction of the arrows, this view being on a larger scale than that of Fig. 1, and;

Fig. 3 is a section taken on the line 3—3 of Fig. 2.

The frame of the machine consists of two connected parts, one of which consists of the motor frame or housing 10 and the other a pillar or standard 11 which is either connected rigidly to or forms an integral extension of the frame or housing 10. The frame or housing 10 constitutes a casing which encloses the motor and driving mechanism of the machine, which mecha-

2

nism is rendered accessible for removal or repair by taking off the bottom plate 12 attached to the frame or housing 10. The driving mechanism contained within the housing or frame 10, consists of a motor and transmission device and from the latter extends a driving shaft 13 projecting out of the housing 10 and available for the coupling thereto of various attachments. For example, in Fig. 1, a mincing or grinding device 14 shown in dotted lines, is coupled to the drive shaft 13.

In the end portion of the pillar or standard 11 an arm 15 is pivotally journaled by means of the pin 16 (Figs. 2 and 3) provided at the end of the arm 15. The opposite or outer end of the arm 15 carries a spindle 35 intended to receive a roller (not shown) but which may cooperate with the interior of a rotatable mixing, kneading or other like receptacle adapted to be coupled to the shaft 13 and rotated thereby. When such a container is used, the machine must be arranged in a position at right angles to that shown in Fig. 1, so that the shaft 13 will then rotate about a vertical axis. Four feet 17, preferably made of rubber or some equivalent soft material, are arranged on or secured to the base plate 12, and these feet serve as supporting members for the machine when the machine is in its upright position or that in which the mixing container is placed in position in coupled relation to the shaft 13. Two corresponding feet 18 are arranged on the side of the motor frame or housing 10 and cooperate with a supporting foot 19 arranged according to the invention, at the upper or outer end of the pillar or standard 11, in supporting the machine in its "reclining" position or that shown in Fig. 1.

Between the pin extension 16 and the pillar or standard 11 is arranged a torsion spring 20 which constantly tends to turn the arm 15 away from the center of the driving shaft 13 into the end position, shown in full lines in Fig. 2. When a kneading, mixing or like container is used, and the same is coupled to the driving shaft 13, the spring 20 thus tends to press the work tool, such as a roller mounted on the spindle 35, against the inside surface of the wall of the container. The pin extension 16 is provided with a radially-extending bolt 22 projecting through an arcuate slot 23 in the upper part of the pillar or standard 11. The bolt 22, as shown in Fig. 2, is preferably screwed into the pin extension 16. The end surfaces 24 and 25 of the slot 23 act as stops or abutments to limit the pivotal movement of the arm 15.

The portion of the bolt 22 which projects beyond the slot 23 is threaded as shown in Fig. 2, and this threaded portion of the bolt 22 adjustably receives a nut 26, preferably formed as a cap nut and which constitutes the supporting foot 19 while at the same time serving as a locking means for the arm 15. To facilitate the manipulation of the nut 26, it is preferably knurled or milled as indicated at 21. The outer end of the nut is preferably provided with a sole piece 27 or the like, of rubber or other similar soft material which is held in position by means of a screw 29 and interposed washer 28.

When the nut 26 is to serve as a locking device for the arm 15, said nut and an interposed friction washer 30, cooperate with a curved face 31 arranged on the pillar or standard 11 outside of and adjacent to the slot 23. Between the outer end of the bolt 22 and the base of the cap nut 26 is provided a compression spring 32 which prevents the nut from being loosened unintentionally.

From the foregoing, the operation of the described structure will be readily understood. By loosening the nut 26, the arm 15 may be swung to any desired angular position within the limits of the slot 23, such as, for example, to the position shown in dotted lines in Fig. 2, and the arm is then maintained in such position by tightening the nut 26. By again loosening the nut, the torsional spring 20 will operate to return the arm to its end position, as shown in full lines in Fig. 2, in which position the nut 26 will be positioned to serve as the supporting foot 19 for the machine, should it be desired to place the machine in the operative position of Fig. 1.

What I claim is:

1. In combination with a machine of the character described having a base whose bottom and a side thereof are provided with supporting feet to enable the machine to be supported in either position of the base, of a standard projecting from such base, an arm pivotally mounted on said standard, and means for securing said arm in any selected position of its pivotal movement, said means including an element serving as a supporting foot for the machine when the latter is positioned to be supported by the feet at the side of the base.

2. In combination with a machine of the character described having a base adapted to be supported on its bottom or on a side thereof provided with supporting feet, of a standard projecting from such base, an arm pivotally mounted on said standard and having a limited pivotal movement with respect to the latter, and means for securing said arm at any selected point in its pivotal movement, said means including a first part projecting radially from said standard and a second part coacting therewith which is frictionally operative against a portion of said standard, said second part including means serving as a supporting foot for the machine when the latter is positioned to be supported by the feet at the side of the base.

3. In a machine of the character described, a base, a standard arising therefrom, an arm having a restricted pivotal movement in said standard, means for urging the arm in one direction, means for locking the arm at any selected point in its pivotal movement, said locking means including a threaded element extending radially from a part of the arm and projecting out of the standard, and a nut adjustable on said threaded element and frictionally operative against a part

of the standard, said nut having a portion serving as a supporting foot for the machine when the machine is arranged in one of its operative positions.

5. In a machine of the character described, a base, a standard arising therefrom, an arm pivotally mounted in said standard, a projection extending radially from a part of the arm, the standard having a slot in which said projection is disposed and which limits the movement of the projection and the swing of the arm, a member adjustable on the projection and adapted to serve as a supporting foot for the machine when the machine is disposed in an operative position, and spring means tending to swing the arm to a position wherein said member becomes operative as a supporting foot.

6. In a machine of the character described, a base adapted for support upon either its bottom or its side, a standard arising from the base, a swinging arm mounted in said standard, the standard having an arcuate slot provided in its wall, a bolt projecting radially from a part of the swinging arm and guided in the slot and limited in its movement by the ends of the slot, a nut adjustable on the end portion of the bolt on the outside of the standard, the standard presenting a curved surface against which the nut is frictionally operative to thereby hold the bolt at any selected point in its travel in the slot, the nut being arranged to serve as a supporting foot at a time when the base is resting upon its side.

7. In a machine as provided for in claim 5, wherein the outer surface of the nut is provided with a soft sole member; wherein spring means is provided for normally positioning the arm in a position wherein the nut can act as a supporting foot, and wherein fixed supporting feet are provided on the side of the base for cooperation with the nut in supporting the machine on its side.

8. In combination with a machine of the character described having a base whose bottom and a side thereof are provided with supporting feet to enable the machine to be supported in either position of the base, of a member projecting from such base, an arm having a portion angularly movable in said member between definite limits, a locking device arranged to hold said arm in any desired position in its range of angular movement, said locking device including an element disposed exteriorly of said member which is adapted to serve as a supporting foot in the side position of the base when said arm is disposed at one limit of its angular movement.

9. In combination with a machine of the character described having a base whose bottom and a side thereof are provided with supporting feet to enable the machine to be supported in either position of the base, of structure comprising a plurality of parts including a member projecting from the base and an arm carried at the end of such member and angularly movable thereon, and means removed from the base which is fixed to a part of said structure other than said projecting member and serves as a supporting foot for the machine when the latter is positioned to be supported by the feet at the side of the base.

10. In combination with a machine of the character described having a base whose bottom and a side thereof are provided with supporting feet to enable the machine to be supported in either position of the base, of structure including a member projecting from the base, and an arm

carried at the outer end portion of said member and angularly movable thereon, said arm being provided with means which serves as a supporting foot for the machine when the latter is positioned to be supported by the feet at the side of the base.
